UNITED STATES PATENT OFFICE.

WILLIAM WOLFE, OF CRESSON, PENNSYLVANIA.

PUMP-VALVE.

1,293,284.

Specification of Letters Patent.

Patented Feb. 4, 1919.

Application filed January 3, 1917. Serial No. 140,415.

To all whom it may concern:

Be it known that I, WILLIAM WOLFE, a citizen of the United States, residing at Cresson, in the county of Cambria and State 5 of Pennsylvania, have invented new and useful Improvements in Pump-Valves, of which the following is a specification.

The present invention relates to pump valves, and more particularly to valves for 10 use in connection with mining pumps, in which it is desirable that ease of installation and replacement and economy in maintenance is secured.

It has for its object to provide a valve 15 which is composed of few parts; which may be readily installed in constricted areas; and in which the elements are so constructed and relatively disposed as that a minimum repair cost may be secured.

20 In the drawings herewith, I have illustrated one physical embodiment of my invention, but it will be understood that this illustrative disclosure is not restrictive, for it is obvious that variations in structure 25 within the range of mechanical skill may be made without departing from the spirit of my invention.

In said drawings,—

Figure 1 is a view in side elevation of my 30 improved valve.

Fig. 2 is a view in cross-section, of the valve shown in Fig. 1, parts of the valve being shown in elevation for clearness of illustration.

35 Fig. 3 is a bottom plan view.

Fig. 4 is a top plan view, the spring being omitted to more clearly show the construction.

Having reference to the drawings by numbers, like numbers indicating like parts in the several views, 10 indicates the valve-seat section, formed, as clearly shown in Fig. 2, with a stepped outer perimeter, the stepped sections 11 and 12 being screw-threaded and separated by a ledge or landing 13 disposed at right angles to the plane 45 of said screw-threaded sections.

Said seat section 10 is preferably, for 50 strength, provided with arches 14 which spring from the inner periphery of the section and join centrally in a boss or web 15. The arches 14 have their lower edges curved or sloped upwardly toward the orifices of the seat so as to offer little or no resistance 55 to flow which is, of course, upwardly, or in the direction of the arrow in Fig. 2, so that

danger of clogging by reason of solid matter striking against bridging surfaces at right angles to the direction of flow is eliminated.

The upper surface of the reduced section 12 of the seat section 10 is flat and forms a smooth seat for the valve member 16, which is preferably of rubber, although other materials may be substituted therefor. Said valve member 16 is of stepped formation, having the lower section 17 and the reduced upper section 18, which is encircled and engaged by a plate 19 of relatively heavy construction and recessed on its under side to receive the reduced section 18 of the valve member 16, the rim 20 of said plate 19 resting upon the extended rim of the lower section 17 of the valve member 16, as shown in Fig. 2.

By forming the valve member and its plate as shown, a construction is secured in which the valve member is held rigidly against flexure or distortion, insuring always an accurate seating of the valve; sufficient weight is given to steady the movements of the valve; and wear of the valve section is uniform owing to the fact that the valve member if of soft material is held in a condition of rigidity by its encircling and embracing plate. It will be observed that the depending rim 20, bearing upon the outstanding ledge 17 of the valve member 16, is directly over the point of seating contact of the valve member 16 with the seat member 10, so that the seating pressure is exerted directly along the circumferential line of contact of the valve with its seat.

The seating pressure is augmented by means of a spring 21, the lower free end of which rests in a shallow recess 22 formed in the upper surface of the plate 19, the upstanding rim bounding this recess preventing side play and displacement of the lower free end of the spring. The said spring 21 is secured at its upper end to an anchor piece 23 removably mounted, preferably by a screw-thread connection, in the dome or cap-piece 24 of a spider formed of curved, radially disposed arms 25 united at their lower ends by a ring 26, the whole forming a rigid spider which is of generally cone-like conformation.

The bottom ring 26 of the spider is threaded interiorly and engages the upper threaded section 12 of the seat member 10, so that, 110 when assembled it rests upon the ledge 13 between the threaded sections 11 and 12. It

- will be observed that the ring 26 and its attached arms 25, all lie within the circumferential area of the seat section 10 and that there are no projecting parts which extend 5 outside the perimeter of the screw-threaded section 11. The advantage of this is that no special construction of pipe or casing to carry the valve is necessary. As indicated in dotted lines, Fig. 2, the valve will engage any 10 screw-threaded seat of the diameter of the valve-seat section 11, and no interference in its placing or removal is occasioned by parts projecting beyond the periphery of the seat section.
- 15 This is of particular advantage in connection with the installations for which this valve is designed, for the reason that the space within which they are installed is limited and it is desirable that special mountings and enlarged pipes or casings to accommodate them be avoided.
- 20 The anchor piece 23 is preferably formed, as shown, of conical shape, and is snugly engaged by the upper coil or coils of the 25 spring 21 which is preferably of cone formation. The confinement of the upper coils of the spring 21 in the manner shown prevents to a large degree any tendency of the spring to side lash or movement, and tends to 30 confine it to direct movement axially of the valve; and this coupled with the confinement of the lower coil of the spring in the recessed top of the plate 19 gives steadiness and accuracy to the movements of the valve.
- 35 The said anchor piece 23 is provided, in the illustrated embodiment herein, with a spanner-socket 27 (see dotted lines Fig. 2) to receive any suitable spanner tool or wrench for its removal and replacement.
- 40 It will be seen (Figs. 1 and 2) that the outer faces 17 of the valve section 16 and the valve plate 19 are curved or coned to conform to the curvature of the spider arms 25, so that while securing a compact construction the necessary maximum movement 45 of the valve is permitted, this coincidence of curvature of the parts permitting the valve to rise and fall in the spider without interference or danger of jamming.
- 50 From the foregoing, it will be seen that I

have provided a valve which is composed of a minimum number of parts, which may be installed in a pipe or casing of ordinary construction and without special mountings; in which the valve parts proper are so constructed and assembled as to insure accurate seating and effective operation with a minimum wear on the parts; and in which danger of clogging is much reduced.

Such changes as may be made within the 60 skill of the mechanic in departing from the embodiment of my invention herein disclosed are, of course, within the range of my invention.

What I claim is:

1. In a valve, the combination of a seat member having a threaded exterior surface, a valve mounted thereon, a valve retaining spider removably secured to said seat member and lying wholly within the circumferential area thereof, a valve seating spring of conical formation, and an anchor piece of conical formation mounted in the apex of said spider and closely engaging the end coil of said conical spring to control its 70 movements and prevent side lash thereof during operation of the valve.

2. In a valve, the combination of a seat member, a valve mounted thereon and having its upper face dished to provide a circular retaining rib, a valve retaining spider so coupled to said seat member as to lie wholly within the circumferential area thereof, a valve seating spring of conical formation the larger end of which loosely engages the 85 dished upper face of said valve and is held against sidewise movement by said circular rib, and a conical anchor piece removably secured to the base of said spider and engaged by the coil of the smaller end of said 90 spring so as to form an extended bearing therefor and prevent undue side lash of the spring and valve.

In testimony whereof I have hereunto set my hand in presence of two subscribing witnesses.

WILLIAM WOLFE.
